A. H. NOBLE

VANITY CASE

Filed Dec. 10, 1926

Inventor

Arthur H. Noble
By Joseph A. Miller

Attorney

UNITED STATES PATENT OFFICE.

ARTHUR H. NOBLE, OF PAWTUCKET, RHODE ISLAND, ASSIGNOR TO THEODORE W. FOSTER & BROTHER COMPANY, OF PROVIDENCE, RHODE ISLAND.

VANITY CASE.

Application filed December 10, 1926. Serial No. 153,816.

This invention relates to certain new and useful improvements in vanity cases and pertains more particularly to an improvement upon the powder container of Patent No. 5 1,603,243, of October 12, 1926.

The primary object of the invention is to provide an attachment for the container which will more effectively prevent accidental or unintended escape of the powder 10 from the container, which attachment affords a trap for the powder so as to prevent the latter from escaping.

The invention further aims to provide a device of the character mentioned, which is 15 of simple and economical construction, and which can be easily and quickly applied.

In the drawings:—

Fig. 1 is a plan view of the vanity case with which the invention is designed for use; 20 Fig. 2 is a section on line 2—2 of Fig. 1 and

Fig. 3 is a side elevation of the invention in detached position.

The drawings illustrate a vanity case composed of a body 1 having a rim 2 and a 25 hinged cover 3 provided with a mirror 4.

The powder holder is composed of a body having a shouldered bottom 10 provided with a central powder-holding depression or 30 well 11, the bottom 10 affording a ledge which encompasses the well and lies thereabove. A cover 12 is provided for the well and is formed with a shallow central depression 13 which is of less diameter than that of the internal diameter of the ledge 10. The cover 12 is hinged at 14 to the ledge 10 and has a spring catch 15 and a finger piece 16, the catch 15 being formed to spring into an opening 16 provided therefor in the top 35 of the body above the ledge. The powder holder further has a depending rim 18 preferably formed to frictionally engage with and within the rim 2 of the body 1.

For the purpose of preventing escape of 40 the powder from the well 11, a felt pad or equivalent 19 is engaged with the cover 12 on the under face of the latter and is secured in place thereon by means of a metal or other disk 20 which engages the felt disk. 45 A rivet 21 is extended through the disks 19 and 20 and the cover depression 13 and serves to clamp the disk 20 against the pad 19 and the latter against the cover 12.

The felt pad or disk 19 extends beyond the depression 13 and also beyond the clamping disk 20 as to permit its peripheral portion 21 to flare into the offset resultant from the depression 13, which portion 21 provides an effective seal for the well 11, preventing the escape of powder therefrom. 55

The present invention resides in the provision of a ring 30 having its inner circumference flanged downwardly at 31. The ring 30 seats on the ledge 10 and has its periphery formed to snugly fit against the shoulder 60 or wall 33 which latter encircles the ledge 10. Preferably the ring is frictionally held in position, permitting its easy attachment and removal, so as to allow cleaning of the parts. 65 if desired. By referring to Fig. 2, it will be seen that the flange 31 cooperates with the upper side wall 34 of the well 11 to form a circular pocket or trap 32, which will trap the powder and prevent the latter from reaching the pad 21 and thereby escaping. 70 Further, the flange 31 confronts the peripheral edge of the clamping disk 20 and thus provides a further trap 35 which latter allows but a small quantity of the powder to engage the pad. 75

In further addition, the ring 30 raises the seat on which the edge 21 of the pad engages, so that a greater degree of compression of the pad is required as compared with said patent, effecting a firm seating thereof and 80 spreading to seal the closure. 85

Having thus described my invention, what I claim as new and desire to secure by Letters Patent is:—

1. In a loose powder container, having a 90 powder compartment encompassed by a shouldered ledge, a cover for the compartment having a felt pad and a clamping disk for the pad, a ring seated on the ledge and forming a seat for the pad and being engaged with the shoulder and a flange depending from the inner circumference of the ring and spaced from the adjacent side of the compartment and from the disk to form a pair of spaced circular powder traps. 95

2. In a loose powder container, having a powder compartment encompassed by a shouldered ledge, a cover for the compartment having a felt pad, a ring seated on the ledge and against the shoulder and forming 100 a seat for the pad, and a flange depending 105

from the inner circumference of the ring and spaced from the adjacent side of the compartment to form a trap.

and a flange carried by the ring and depending therefrom to form a trap in conjunction with the adjacent side wall of the compartment. ¹⁰

3. In combination with a powder compartment having a shouldered ledge surrounding the same, a cover, a ring forming a seat for the cover frictionally engaged with the shoulder and seated on the ledge,

In testimony whereof I have signed my name to this specification.

ARTHUR H. NOBLE.
